UNITED STATES PATENT OFFICE.

JAKOB GUNTHER, OF BERGISCH-GLADBACH, GERMANY.

INTERNAL-COMBUSTION ENGINE.

1,162,769.

Specification of Letters Patent.

Patented Dec. 7, 1915.

Application filed September 21, 1911. Serial No. 650,577.

To all whom it may concern:

Be it known that I, JAKOB GUNTHER, a subject of the Emperor of Germany, residing at Bergisch-Gladbach, Germany, have 5 invented certain new and useful Improvements in Internal-Combustion Engines, of which the following is a specification.

In internal combustion engines wherein for the purpose of introducing and atomizing the liquid charge use is made of a displacer piston moving in a displacer cylinder which is connected to the working cylinder, the supply of the fuel has hitherto been effected through a special fuel conduit connecting the space (high pressure chamber) in which the pressure is increased by the displacer with the space of lower pressure (combustion chamber) and into which the charge is introduced for the purpose of being atomized by the air current prior to its passage or during its passage to the combustion chamber. It has now been found that the said special conduit or passage for the fuel may be entirely dispensed with by 25 guiding the displacer piston in a prismatic (mostly hollow cylindrical) guide or cavity with sufficient play so that the intermediate space thus produced itself serves as an atomizing passage provided the combustion chamber is so enlarged immediately behind that space that the fuel supplied thereto is not blown along the wall but is atomized into the space clear of the walls. In this case during the movement of the displacer in its guide or cavity the fuel must be introduced at such a point that it is caused to be atomized by the air current. It is therefore introduced preferably either into the space itself or directly at its terminal 40 in the combustion chamber. By these means the special fuel conveying passage which often gives rise to soot accumulations may be dispensed with and the wear of the displacer in its guide is avoided.

45 Several constructional forms of the invention are shown in the accompanying drawing in which similar reference letters indicate similar parts.

Figure 1 is a sectional view of the cylinder and the head of the cylinder according to 50 the invention, the combustion chamber proper being shown in the head of the cylinder. Fig. 2 is a similar view showing another form of the invention, the combustion chamber being in the head of the cylinder, while Fig. 3 is a similar view showing a

third form, the combustion chamber proper being situated between the head of the cylinder and the piston.

In Fig. 1 the main piston *a* is shown at 60 the end of its compression stroke. Its cone-shaped inner end *b* forms with the adjacent likewise cone-shaped cylinder-wall an annular high pressure chamber *c*. The bottom of the piston terminates in a generally prismatic (in the present instance cylindrical) displacing member *d* having an acutely rounded end and projecting with sufficient play into the prismatic (in the example cylindrical) displacement guide or cavity *e* 65 so that a narrow annular space *f* is formed which separates the conical combustion chamber *k* from the high pressure chamber *c*. In the rear of the annular space is a conical throttling passage *v* adapted to deflect the air current from the walls of the combustion chamber. Terminating in the end of the throttling passage is the nozzle *g* serving for the introduction of the liquid fuel.

The operation of this device is as follows:—During its movement in the direction of the arrow the working piston compresses a suitable charge of air. Before the end of the compression stroke the displacer *d* enters the cavity *e* thereby separating the cylinder interior in the high pressure chamber *c* from the combustion chamber *k* the connection being maintained solely by the throttling passage through which a short 75 violent air current is caused to travel from the former to the latter. At the same time fuel under pressure is introduced through the nozzle *g* by means of a fuel pump (not shown). The air which as shown in the 80 drawing is forced toward the center of the combustion chamber in the form of a conical jet atomizes the fuel and after intimately mixing therewith ignites it. While in a cold state the engine may be started by 85 means of a highly inflammable fuel such as benzine and driven thereby for a few minutes until the slowly combustible working fuel is supplied to it.

Fig. 2 shows a second constructional example 90 where the air jet does not assume a conical shape as in Fig. 1 but a cylindrical form owing to the cylindrical form of the surface which guides the air current. In this case the wall of the combustion chamber 95 must be enlarged with regard to the throttling passage *f* as otherwise the atomized

oil would be blown along the wall and consequently its combustion would be defective.

In Fig. 3 a third constructional form is illustrated wherein the high pressure chamber *c* is located in the rear end of the cylinder and the combustion chamber *k* is of an annular shape. The projection of the piston or displacer *d* in this form extends, when the piston is in its inner position, close to the inner wall of the high pressure chamber *c*, while the conical end surface *b* of the piston, in this position, is spaced a certain distance from the inner surface of the head of the cylinder whereby the ring like combustion chamber *k* is formed. The air compressed in the high pressure chamber *c* flows in a reverse direction through the ring like throttling passage *f* into this combustion chamber *k*. The fuel is introduced by means of one or a plurality of nozzles *g* terminating at the throttling passage *f*. The manner in which also in this case the connecting part forming a portion of the wall must be tapered between the displacing and working piston in order to keep the atomized oil away from the wall is clearly shown in the drawing.

What I claim and desire to secure by Letters Patent is:—

1. In an internal combustion engine, the combination of a cylinder, a combustion chamber and a passage between said cylinder and said combustion chamber, said passage being of smaller diameter than the combustion chamber, a piston within said cylinder, a projection on said piston, said projection being adapted to enter the passage when the piston approaches to its inner position, thus forming with said passage an annular

throttling space, through which the air compressed in the cylinder is forced and means for introducing fuel into said annular throttling space so as to force a stream of air and fuel into the combustion chamber without spreading the fuel on its walls.

2. In an internal combustion engine, in combination, a cylinder, a combustion chamber and a connecting passage between said cylinder and said combustion chamber, said passage being arranged co-axially and concentrically with said cylinder, the entrance of said passage into said combustion chamber being of smaller diameter than the combustion chamber, a piston within said cylinder, said piston having at its inner end a projection arranged co-axially and concentrically with said cylinder and said piston, said projection being of smaller diameter than said passage and adapted to enter the passage when the piston approaches and reaches its inner position, thus forming with said passage an annular throttling space through which the air compressed in the cylinder is forced freely into the combustion chamber and means for introducing fuel into said annular throttling space and the current of air forced through it, said fuel flowing before the atomization thereof by the air in the free space in the head of the cylinder where its combustion which is free from soot is started.

In testimony whereof I affix my signature in presence of two witnesses.

JAKOB GUNTHER.
